(57) **CLAIM**

The ornamental design for a cutlery handle, as shown and described.

DESCRIPTION

FIGS. 1, 2 and 3 are perspective views of a new cutlery handle mounting various implements;

FIG. 4 is a first side elevational view of the handle of FIG. 1; FIG. 5 is a second side elevational view of the handle of FIG. 1;

FIG. 6 is a top plan view of the handle of FIG. 1; and, FIG. 7 is a bottom plan view of the handle of FIG. 1. The broken lines shown in the drawings are for illustrative purposes only and form no part of the claimed design.

1 Claim, 5 Drawing Sheets

FIG. 4

FIG. 5

FIG. 7

FIG. 6
